CONTROL SYSTEM FOR MOTOR DRIVEN APPARATUS

Paisley B. Harwood and Niels L. Mortensen, Milwaukee, Wis., assignors to Cutler-Hammer, Inc., Milwaukee, Wis., a corporation of Delaware

Application March 19, 1932, Serial No. 600,000

8 Claims. (Cl. 242—75)

This invention relates to control systems for motor driven apparatus, and while not limited thereto is particularly applicable to systems for governing the operation of motor driven reels such as are employed in connection with mills for rolling strip steel.

In the manufacture of various materials such as cold rolled strip steel the finished product is wound in coil form upon a reel. In winding such material it is desirable to maintain a predetermined substantially constant tension thereon, and it is also desirable if the mill is stopped for any reason, as for example to permit gauging of the material, to maintain tension on the material to prevent loosening thereof upon the reel.

The present invention has among its objects to provide an improved control system for motor driven reels which meets the above noted requirements.

Another object is to provide an improved control system of the aforesaid character which provides for quick starting of the reel for taking up of slack in the material upon commencement of the winding operation, and which prevents excessive pull upon the material when the same becomes taut.

Various other objects and advantages of the invention will hereinafter appear.

The accompanying drawing illustrates a control system embodying the invention which will now be described, it being understood that the system may be used in installations of various types, and that the same may be modified in various respects without departing from the spirit and scope of the appended claims.

In the drawing,

Figure 1 schematically illustrates the invention as applied to a collapsible reel associated with a mill for rolling strip steel, and

Fig. 2 diagrammatically illustrates the circuits and apparatus for controlling the reel shown in Fig. 1.

Referring to Fig. 1, the same illustrates a reel 1 for winding strip material 2 as the same passes from the finishing rolls of a mill 3. The reel illustrated is of a type commonly employed in connection with mills for rolling strip steel, and includes a plurality of collapsible parts 4 which are arranged to slide radially within suitable recesses in a cylindrical drum 5. Drum 5 is rotatably mounted upon a shaft 6 and the collapsible parts 4 are connected by links 7 to a spider 8 fixed to said shaft. Drum 5 has a foot operated brake 9 associated therewith, and when said part 4 is restrained by said brake and shaft 6 is rotated

in a counterclockwise direction, spider 8 causes links 7 to straighten and move the parts 4 radially so as to increase the effective diameter of the reel. Drum 5 also carries cooperating stationary and movable jaws 10 and 11. Jaw 11 is operatively connected to spider 8 and upon movement of parts 4 to their expanded positions said jaw is adapted to cooperate with jaw 10 to grip the forward end of strip 2. When the material is gripped and the reel is rotated in a counterclockwise direction sufficiently to tension the strip, brake 9 can be released and the tension on the strip acting in opposition to the driving force on the reel serves to maintain parts 4 in their expanded positions. An electromagnetic brake B is also associated with drum 5 for effecting collapse of the reel as hereinafter set forth.

As shown in Fig. 1, mill 3 is provided with a driving motor 12 and reel 1 is arranged to be driven through the medium of an electromagnetic clutch C by a motor 14. A push button controlled starter 15 of any suitable type is provided for starting and stopping the mill motor 12, and a controller 16 of the character shown in Fig. 2 is provided for controlling the reel 1.

As shown in Fig. 2 the reel motor 14 is of an adjustable speed direct current type, the same having an armature A, a series field winding F and a shunt field winding F¹, the latter being connected across a supply circuit indicated by lines L¹—L² in series with an adjustable regulating resistance R¹. The control means for said motor includes electroresponsive line switches 20 and 21, electroresponsive accelerating switches 22, 23 and 24, and an electroresponsive regulating switch 25. Switches 20 and 21 provide for connection of the armature A and series field winding F of the motor across lines L¹—L² in series with resistance sections R², R³, R⁴ and R⁵. Switches 22, 23 and 24 are arranged to shunt resistance sections R², R³ and R⁴, respectively, and are controlled to close progressively after suitable intervals in accordance with any known system of acceleration. Regulating switch 25 is arranged to shunt a portion of resistance R¹ in the shunt field circuit of the motor, and the same is controlled as hereinafter set forth to regulate the shunt field strength of the motor so as to maintain a substantially constant tension on the material during winding thereof.

An electroresponsive switch 26 is provided for connecting the operating winding of clutch C across lines L¹—L² in series with resistance sections R⁷, R⁸ and R⁹. Resistance sections R⁷, R⁸ and R⁹ are normally shunted by an electrore-

sponsive switch 27 having an operating winding 27^a connected in series with the operating winding of clutch C and normally open electroresponsive switches 28 and 29 are provided for shunting 5 resistance sections R⁷ and R⁹, respectively. The system also includes an electroresponsive switch 30 for connecting the operating winding of brake B across lines L¹—L².

The control means for the aforescribed 10 switches includes a plurality of electroresponsive relays and controlling push buttons which will now be described.

An electroresponsive relay 31 is provided for controlling energization of line switches 20 and 15 21 associated with the reel motor 14, and said relay also serves to establish connections which provide for energization of the clutch C and brake B by an electroresponsive relay 34. The energizing 20 circuit for relay 31 is controlled by a normally closed push button 32 and a normally open push button 33 and the energizing circuit for relay 34 is under the control of an electroresponsive relay 35 controlled by a normally closed push button 36 and a normally open push button 37. Relay 35 25 also serves to establish connections which provide for energization of regulating switch 25 by normally closed contacts 24^a associated with accelerating switch 24 or by a normally open relay 38 having an operating winding 38^a connected 30 across resistance section R⁵. An electroresponsive relay 39 is provided for establishing an energizing circuit for the clutch resistance control switch 29 through the medium of relays 31, 34 and 35, and as hereinafter set forth the energizing 35 circuit for relay 39 is under the control of certain of the aforementioned relays and is also controlled by a relay 40 associated with the mill 40 starter 15. As hereinbefore stated, starter 15 is of a push button controlled type and as shown in Fig. 2 the operating winding of relay 40 is arranged to be connected across a supply circuit indicated by lines L¹¹—L¹² by the stop push button 41 of said starter. The clutch control switch 28 is controlled by a normally closed electroresponsive 45 timing relay 42. This relay is provided with a dash pot for retarding closing movement thereof and its energizing circuit is controlled by an electroresponsive relay 43 associated with starter 15. As shown in Fig. 2, the operating winding 50 of relay 43 is adapted to be connected across the supply circuit L¹¹—L¹² by the stop push button 41 of starter 15 and auxiliary contacts 44 which it is assumed are associated with the line switch 55 of said starter and are adapted to close upon establishment of power connections for the mill motor 12. The system also includes a limit switch 45 which as hereinafter set forth controls a maintaining circuit for relay 39. Said limit switch is associated with the reel and is adapted to open 60 when the reel is in proper position to receive a strip.

The operation of the circuit connections of the aforescribed system will now be more fully set forth.

65 The reel motor is started by depressing push button 33. Closure of push button 33 effects response of relay 31 by connecting the operating winding thereof across lines L¹—L² through the medium of push button 32. Upon response of 70 relay 31 the contacts 31^a thereof shunt push button 33 to maintain said relay in closed position and the contacts 31^b thereof connect the operating windings of line switches 20 and 21 in parallel across lines L¹—L². Switches 20 and 21 there- 75 fore respond to connect the armature A and

series field winding F of reel motor 14 across lines L¹—L² in series with resistance sections R² to R⁵, inclusive. Accelerating switches 22, 23 and 24 then respond progressively after suitable intervals to exclude resistance sections R², R³ and R⁴. 80 During starting of motor 14 the operating winding of regulating switch 25 is connected across lines L¹—L² by the auxiliary contacts 24^a associated with accelerating switch 24 and contacts 35^a associated with relay 35. Switch 25 is thus held in closed position, and as is apparent the same shunts a portion of regulating resistance R¹ to provide maximum current in the shunt field winding pending response of accelerating switch 24. Upon closure of accelerating switch 24 the contacts 24^a thereof open to deenergize switch 25 and the current in the shunt field winding F¹ is reduced to provide for operation of the reel motor at a predetermined high speed determined by the adjustment of resistance R¹. To 85 effect stopping of the reel motor 14 at any time push button 32 is depressed and relay 31 then drops out to deenergize the line switches 20 and 21.

When a strip 2 comes through the finishing 100 rolls 3 of the mill the reel motor 14 is in operation and the operator then inserts the forward end of the strip between jaws 10 and 11 of reel 1 and simultaneously closes push button 37 and applies brake 9. To simplify this operation push button 105 37 is preferably associated with brake 9 so that the same closes when said brake is applied. Closure of push button 37 effects response of relay 35 by connecting the operating winding of said relay across lines L¹—L² through the medium of normally closed push button 36. Relay 34 responds immediately upon response of relay 35, the operating winding thereof being then connected across lines L¹—L² through the medium of push button 36 and the contacts 35^b of relay 35. Response of 110 relay 34 effects closure of the clutch control switch 26 and the brake control switch 30 since the operating windings of these switches are then connected in parallel across lines L¹—L² through the medium of contacts 31^b 115 of relay 31 and contacts 34^a of relay 34. Closure of switch 26 connects the operating winding of clutch C directly across lines L¹—L² through the medium of relay 27 to effect quick engagement of said clutch and closure of switch 30 connects the 120 operating winding of brake B directly across said lines to effect quick release of said brake.

Reel 1 now begins to rotate in a counterclockwise direction and upon initial rotation thereof 125 brake 9 causes the jaws 10 and 11 of said reel 130 to grip the strip 2 and the parts 4 thereof to move to their expanded positions. The strip is then wound upon the expanded reel and since the reel motor is operating at high speed due to inclusion of regulating resistance R¹ in the shunt field circuit thereof the reel is accelerated rapidly to effect quick take-up of the slack between the reel and the rolls 3. Before the strip between the reel and rolls 3 becomes taut the current in the clutch winding C builds up to a value sufficient to effect 140 response of relay 27. Response of relay 27 includes resistance sections R⁸ and R⁹ in series with the operating winding of clutch C, the resistance section R⁷ being at this time shunted by switch 28 which is energized through the medium of timing 145 relay 42. The current in the clutch winding is thus reduced to a value which provides for slippage of the clutch at a torque which is insufficient to produce excessive strain on the strip when the same becomes taut. 150

Upon taking up of the slack between the reel 1 and the rolls 3 the operator releases brake 9 and push button 37. Relay 35 is then deenergized but upon dropping out of said relay relay 34 is maintained energized by a circuit extending through its contacts 34^b and the normally closed push button 36. As is apparent, when the mill is in operation relays 40 and 43 are held in their attracted positions as shown in the drawing, and upon dropping out of relay 35 relay 39 is energized by a circuit extending from line L¹ through push button 36 through contacts 34^b of relay 34, through relay 40 to and through the operating winding of relay 39 and through contacts 43^a of relay 43 to line L². Upon response of relay 39 the clutch control switch 29 is energized by a circuit extending from line L¹ through contacts 31^b of relay 31, through contacts 34^a of relay 34, through contacts 39^a of relay 39, to and through the operating winding of switch 29 and through contacts 35^a of relay 35 to line L². Switch 29 thus responds to exclude resistance section R⁹ from the clutch energizing circuit and exclusion of such resistance increases the current in the operating winding of the clutch to a value which prevents slippage of the clutch during the winding operation.

During winding operations relay 38 acts through the medium of regulating switch 25 to control the speed of reel motor 14 in a manner whereby a predetermined substantially constant tension is maintained on the strip. When the tension on the strip exceeds a predetermined value, the current in the armature circuit of motor 14 effects response of relay 38. The operating winding of regulating switch 25 is then connected across lines L¹—L² through the medium of contacts 35^a of relay 35 and said switch responds to shunt a portion of the regulating resistance R¹ to thereby increase the current through shunt field winding F¹. This causes the motor 14 to slow down, which in turn reduces the tension on the strip 2 and consequently reduces the load on said motor. Upon a given reduction of the load on motor 14 relay 38 drops out to deenergize regulating switch 25, whereupon the above regulating cycle will be repeated. It will thus be apparent that the action of relay 38 will be vibratory to thereby maintain a predetermined average tension on strip 2.

When it is desired to stop the mill for any reason, as for example to permit gauging of the material, push button 41 is momentarily depressed, and as hereinbefore stated this operation causes controller 15 to effect stopping of the mill motor 12. Relay 40 then drops out momentarily to interrupt the aforesaid energizing circuit for relay 39 and relay 43 drops out to prevent reestablishment of this energizing circuit pending restarting of the mill motor 12. Upon deenergization of relay 39 the contacts 39^a thereof interrupt the aforesaid energizing circuit for switch 29 and said switch thus moves to open position to insert resistance section R⁹ in series with the operating winding of clutch C. Also upon dropping out of relay 43 the contacts 43^b thereof connect the operating winding of timing relay 42 across lines L¹—L² and said relay in responding deenergizes switch 28 to include resistance section R⁷ in series with the operating winding of clutch C. Thus during stopping of the mill resistance sections R⁷, R⁸ and R⁹ are included in circuit with the operating winding of clutch C and such resistances limit current in the clutch circuit to a value sufficient to maintain

switch 27 in closed position and to provide for slippage of the clutch at a torque of low value which maintains sufficient tension on the strip to prevent collapse of the reel upon stopping of the mill.

When the mill is restarted relay 43 is energized by auxiliary contacts 44 associated with the mill controller, and upon response of relay 43 the aforesaid energizing circuit for relay 39 is reestablished and also timing relay 42 is deenergized to permit closure thereof against the action of its associated dash pot. Relay 39 in responding reestablishes the aforesaid energizing circuit for switch 29 and after a period which is sufficient for the mill to be brought up to speed relay 42 returns to normal position to reestablish the aforesaid energizing circuit for switch 28. Thus during restarting of the mill resistance section R⁹ is first shunted to provide for slippage of the clutch at a given increased torque, and when the mill is brought up to speed resistance section R⁷ is shunted to prevent slippage of the clutch upon continuance of the winding operation.

To stop the reel upon completion of a coiling operation, push button 36 is depressed and if the reel is then in the proper position for receiving the next strip the aforesaid energizing circuit for relay 34 is interrupted and said relay in dropping out deenergizes the clutch control switch 26 and brake control switch 30. Clutch C is thus released and the reel is brought to a quick stop and collapsed under the action of brake B.

If the reel is not in the proper position for receiving the next strip, at the moment push button 36 is depressed the limit switch 45 associated with the reel is closed and maintains a shunt circuit around said push button to prevent dropping out of relay 34. However, if push button 36 is maintained depressed until the reel arrives at the proper position for receiving the next strip, limit switch 45 opens and relay 34 then drops out to stop the reel as above set forth. Upon completion of a winding operation the reel motor 12 remains in operation, but as is apparent the same may be stopped at any time by depressing push button 32.

What we claim as new and desire to secure by Letters Patent is:

1. The combination with a revoluble reel for coiling stock fed thereto, of driving means for said reel including an electromagnetic clutch and means for controlling said clutch including means for limiting the torque transmitted thereby upon commencement of a coiling operation and also upon arrest of the stock during a coiling operation.

2. The combination with a machine operating to deliver stock to be coiled and a revoluble reel for the coiling of such stock, of a driving motor for said reel, an electromagnetic clutch for establishing a driving connection between said reel and said motor, and means for controlling energization of said clutch including means for varying the current supplied thereto to provide for limitation of the torque transmitted thereby upon commencement of a winding operation and also upon stopping of said machine.

3. The combination with a delivery means for stock to be coiled and a revoluble reel for the coiling of such stock, of a driving motor for said reel, an electromagnetic clutch for controlling a driving connection between said reel and said motor, means for establishing an energizing cir-

cuit for said clutch but only upon starting of said motor, and means associated with said former means for varying the value of the current supplied to said clutch to provide for slippage thereof at a given limited torque upon commencement of a winding operation and for thereafter rendering the same capable of transmitting an increased torque.

4. The combination with a machine operating 10 to deliver stock to be coiled and a revoluble reel for the coiling of such stock, of a driving motor for said reel, an electromagnetic clutch responsive to establish a driving connection between said motor and said reel, means for establishing 15 an energizing circuit for said clutch but only upon starting of said motor, and means associated with said former means for varying the value of the current supplied to said clutch to provide for slippage thereof at given limited torques upon commencement of a winding operation and upon 20 stopping of said machine during a winding operation and to also render the same non-slipping after commencement of a winding operation.

5. The combination with a strip mill, of a reel 25 for winding strip material delivered by said mill, a driving motor for said reel, an electromagnetic clutch responsive to establish a driving connection between said motor and said reel, means for establishing an energizing circuit for said clutch 30 and for varying the current supplied thereto to provide for slippage thereof upon commencement of a winding operation and to render the same non-slipping after the strip between said reel and said motor becomes taut and means for controlling 35 the current supplied to said motor to maintain a substantially constant tension on the strip during winding thereof.

6. The combination with a strip mill, of a reel 40 for winding strip material delivered by said mill, a driving motor for said reel, an electromagnetic clutch responsive to establish a driving connection between said motor and said reel, means re-

sponsive only upon engagement of said clutch to control said motor to maintain a substantially constant tension on the strip during winding thereof, means for establishing an energizing circuit for said clutch but only upon starting of said 80 motor, and means associated with said latter means for controlling the current supplied to said clutch to provide for slippage thereof upon commencement of a winding operation and for thereafter rendering the same non-slipping.

7. The combination with a strip mill, of a reel 85 for winding strip material delivered by said mill, a driving motor for said reel, an electromagnetic clutch responsive to establish a driving connection between said motor and said reel, electro-responsive means operable only upon starting of said motor to establish an energizing circuit for said clutch, a resistance connected in the energizing circuit for said clutch, means normally excluding said resistance from said circuit and responsive upon a given current condition in said circuit to include the same, and manually controlled means for shunting a portion of said resistance.

8. The combination with a strip mill, of a collapsible reel for winding strip material delivered by said mill, said reel having a normally engaged electroresponsive brake associated therewith, a driving motor for said reel, a clutch responsive to establish a driving connection between said 105 motor and said reel, means for simultaneously energizing said brake and said clutch but only upon starting of said motor, and for simultaneously deenergizing said clutch and said brake upon completion of a winding operation, said 110 means including means for preventing deenergization of said clutch and said brake except upon positioning of said reel in a given angular position.
